UNITED STATES PATENT OFFICE.

MARQUIS J. TODD, OF BUFFALO, NEW YORK.

DESIGN FOR A HARROW-FRAME.

SPECIFICATION forming part of Design No. 22,692, dated August 8, 1893.

Application filed June 1, 1893. Serial No. 476,296. Term of patent 14 years.

To all whom it may concern:

Be it known that I, MARQUIS J. TODD, of Buffalo, in the county of Erie and State of New York, have invented and produced a certain new and original Design for Harrow-Frames; and I do hereby declare the following to be a full, clear, and exact description of the invention, such as will enable others skilled in the art to which it appertains to make and use the same.

This is a design for harrow frames.

In the accompanying drawing, the figure is a plan view of a harrow-frame showing my design.

The leading features of my design are:— First, the diamond-shaped openings B and V-shaped elongations or extensions C. The openings B are produced by bars *a* and at one end of each of said openings are the V-shaped elongations or extensions which are produced by continuations of bars *a* which are prolonged into disconnected parallel por-

tions *b* and they are then carried diagonally inward toward each other, as at *b'*, and then again into parallel meeting portions *b²*; second, the diamond-shaped openings B and V-shaped elongations or extensions C in connection with the central openings also having V-shaped elongations or extensions; third, the openings B and elongations C in connection with the forward approximately oblong openings A, E which are comprised within the bars of the frame extended.

I claim—

The design for a harrow-frame, substantially as herein shown and described.

In testimony whereof I have signed this specification in the presence of two subscribing witnesses.

MARQUIS J. TODD.
